W. O. Randlett.

INVENTOR.

ATTORNEY.

UNITED STATES PATENT OFFICE.

WILLIE O. RANDLETT, OF RICHMOND, VIRGINIA, ASSIGNOR OF ONE-HALF TO CYRUS B. BUCHANAN.

DEVICE FOR CLEANING FLUME GRATINGS.

1,420,283.

Specification of Letters Patent. Patented June 20, 1922.

Application filed February 15, 1921. Serial No. 445,246.

To all whom it may concern:

Be it known that I, WILLIE O. RANDLETT, a citizen of the United States, residing at Richmond, in the county of Henrico and State of Virginia, have invented certain new and useful Improvements in Devices for Cleaning Flume Gratings, of which the following is a specification.

My invention relates to improvements in devices for cleaning flume gratings.

The object of my invention, is to provide a device of this character, in which a frame carrying, a pivoted rake, at its lower end, is lowered to the lower end of the flume grating and in its upward movement carries with it all trash, accumulated against the grating, and at the same time provides means whereby the trash after it has been carried up beyond the upper end of the grate bars, can be dumped to tilt the rake so that the trash will be readily discharged therefrom and at the same time allowing the rake to be locked and remain in said tilted position until the frame carrying the same is lowered to the bottom of the grating, thus allowing the free downward movement thereof past any trash that has accumulated.

Another object of my invention is to provide a cleaning device of this character which is adapted to be carried along and used in connection with any one of a series of gratings and thus necessitating but a single cleaner for any number of gratings leading to the series of turbines for which my device is more specifically constructed.

A still further object of my invention is to provide a simple cheap and effective device of this character in which all operating parts are above water level, thus preventing any liability of the device or its operating mechanism being clogged by trash and at the same time permitting the ready repair of all parts, and having certain details of structure and combination of parts hereinafter more fully set forth.

In the accompanying drawings—

Fig. 1 is a perspective view of my cleaning device applied to one grating of a series showing it in its lowered position.

Fig. 2 is a front view of Fig. 1 showing the rake in its raised position the same as Fig. 1.

Fig. 3 is a vertical transverse sectional view showing the position of the rake while moving upwardly cleaning the grating and showing in dotted lines the rake in its dump-

ing position for releasing the trash and also the position it assumes while being lowered into the flume.

Fig. 4 is a vertical sectional view of the device showing a mechanism for positively forcing the frame carrying the rack down in the event that it will not descend by gravity.

Referring now to the drawings 1 represents the grating of a flume for use in turbines or other water power plants and which are arranged in series, one grating to each turbine. These gratings usually have the grate bars vertically disposed but in many instances they are obliquely arranged. At the ends of the gratings are arranged the vertically or obliquely arranged channel irons 2 and 3 which extend parallel with the grating and which form guide ways for the cleaning frame as shown in Fig. 1 of the drawings. The channel irons 3 between the several series of gratings are made of a double form so that the one channel iron forms a guide for two gratings.

My improved cleaning device consists of a rectangular frame 4 made of angle irons 5, 6, 7 and 8 bolted or riveted together in any desired manner and the upper and lower angle irons 5 and 7 are braced by the two stay bolts 9 and 10, and adapted to be reinforced by additional stay bolts and cross braces. The two end angle irons have one flange extending beyond the upper and lower angle irons and adapted to extend into the channel irons 2 and 3 carried by the gratings and whereby the whole rake carrying frame slides up and down in the channel irons and maintains its spaced relation to the grating. The cleaner carrying frame is supported by two cables 11 and 12 and whereby it is readily raised and lowered into the channel irons and slides down the same to the lower end of the grating, it being understood that the channel irons extend a sufficient distance above the grating to at all times support the frame when it has been raised to bring the rake above the grate bars.

While I have shown the frame supported by cables it will be understood that, in the place thereof rods could be used in which event positive means would be used for drawing the rods up and also forcing them down in which event the frame would be positively forced down and would not depend upon gravity.

When the cables are used a positive oper-

ation could be used for forcing the frame down and in which event it would consist of pulleys 13 carried by the channel irons 2 and 3 at a point a little above the grating and 5 cables 14 would pass under the pulleys and be secured to the upper end of the frame and by pulling up on the cable the frame 4 would be forced down.

The lower horizontal angle iron 7 is spaced 10 from the irons 6 and 8 by the short angle irons 15 and 16 which spaces the iron 7 therefrom. The angle iron 7 is provided with bearings 17 in which are mounted the pintles 19 carried by the rake 20. These pintles 19 are intermediate the ends of the rake fingers and said rake fingers are formed or connected by the two angle irons 21 and 22 which throws the greater portion of the weight on the inside of the pintles and thus 15 the rake would be normally held in the position shown in Fig. 1. The rake at the center has a rod or bar 23 pivotally connected thereto at 24 and which extends upwardly and passes through an opening 25 in the angle iron 5 and has a cable 26 attached thereto whereby the rod may be drawn upwardly for rocking the rake on its pintle and throw it in the position shown in Fig. 4 of the drawings for dumping the rake. The 20 rod 24 has a notch 27 in its edge and into which extends the cam member 28 pivoted at 29 whereby the bar is locked in its raised position and will hold the rake so that it will readily pass downwardly by any trash that 25 has accumulated against the grate bars. The cam member 28 also grips the rod and holds it in its lowered position with the rake in the position shown in Fig. 1 so that the weight of the trash will not tilt the rake in 30 its upward movement, though normally this would be unnecessary. This cam member 28 is operated by a cable 30 whereby the bar is released after the frame has been lowered in the water and reaches the lower end of the 35 grating, so that the weighted end of the grate throws it in a horizontal position.

The end of the rake fingers have a horizontal bar connecting the outer ends thereof and said bar engages the outer face of the 40 grate bars so that the ends of the rake fingers will not extend between the grate bars and thus allow the free upward passage of the rake by the horizontal supports of the bars so that the frame and rake can travel above 45 the upper end of the grating and the trash dumped on the wall or support above the grating. As heretofore stated these gratings are usually arranged in series, one grating for each turbine and by having the hoisting 50 and lowering mechanism arranged on a traveling member supported above the series of gratings the frame can be moved along and lowered in any of the guides opposite any grating and thus it requires only one 55 cleaner for any number of gratings. It will

be seen that a cleaner when not used is supported in the upper ends of the guide rails 2 and 3 above the water and is not subject to the usual wear and tear of the water and trash constantly accumulating against the 70 same.

In operation the frame is placed between the guide rails 2 and 3 and the cable 20 is drawn up thus drawing the rod 24 up until the cam member 28 enters the notch and 75 holds the rake in the position shown in Fig. 4 of the drawings. This throws the ends of the rake fingers away from the grate bar and allows it to pass by any trash that is held by the flow of the water through the 80 grate against the same. When the frame reaches the lower end of the grate bar the cam member 28 is released the rake by gravity assumes the position shown in Fig. 1 of the drawings. The cam member again locks 85 the bar 24 in its lowered position and the cables are worked to draw the frame up in the guides. When traveling up the bar carried by the rake fingers bears against the grate bars and carries every thing up to the 90 upper end and lifts it from the water. The cam 28 is released and if the weight of the trash is not sufficient to dump the rake, it can be forced down by hand.

Having thus described my invention, 95 what I claim as new and desire to secure by Letters Patent is:—

1. The combination with a grating of the character described, guides adjacent said grating, a frame sliding in said guides, a 100 pivoted rake carried by the lower end of the frame, means for locking the rake in its tilted position when lowering the frame in the guides and also in its working position.

2. The combination with a grating of the character described, guides adjacent said grating, a frame sliding in said guides, means for raising the frame in the guides, a pivoted rake carried by the lower end of the 105 frame and means for locking the rake 110 away from the grating during its downward movement and against the grating in its upward movement.

3. The combination with a grating of the character described, guides adjacent said 115 grating, a frame sliding in said guides, means for raising the frame in the guides, a pivoted rake carried by the lower end of the frame, means for dumping the rake, means for holding the rake in its dumped position to 120 bring it away from the grating during the downward movement of the frame, means for releasing the rake after the frame has reached its lower position to bring it in engagement with the grating and means for 125 locking the rake in its last mentioned position during the upward movement of the frame.

4. The combination with a grating of the character described, guides adjacent there- 130

to, a frame sliding in said guides, a rake pivoted intermediate its front and back, and held in operative position by gravity, a rod for tilting the rake, means for locking the rod attached to the sliding frame with the rake in its tilted position, and means for releasing said locking means when the frame has reached the lower end of the grating whereby the rake may assume its working position.

5. The combination with a grating of the character described, guides adjacent said grating, a frame sliding in said guides, a rake intermediately pivoted, and held in an operative position by gravity, a rod for tilting the rake, means for locking the rod with the rake in its tilted position, means for releasing said locking means when the frame has reached the lower end of the 15 grating to allow the rake to assume its working position and for locking the rake in its working position.

6. The combination with a grating of the character described, guides adjacent said grating, a frame sliding in said guides, a rake intermediately pivoted and held in operative position by counter weights, a rod for tilting the rake, a cam member for locking the rod with the rake in its tilted 25 position, means for releasing the cam when

the frame has reached the lower end of the grating, and allowing the counter weight to move the rake in operative position, and means for raising and lowering the frame in the guides.

7. The combination with a grating of the character described, guides adjacent said grating, a frame sliding in said guides, a rake intermediately pivoted and held in operative position by counter weights, a 40 rod for tilting the rake, a cam member for locking the rod with the rake in its tilted or working position, means for releasing the cam when the frame has reached the lower end of the grating, and allowing the 45 counter weight to move the rake in operative position, and means for raising and lowering the frame in the guides.

8. The combination with a grating of the character described, a pivoted rake carried 50 by the lower end of the frame, means for locking the rake in its tilted or working position.

In testimony whereof I affix my signature in the presence of two witnesses,

WILLIE O. RANDLETT.
